By Victor J. Evans
Attorney.

UNITED STATES PATENT OFFICE.

EUDORA B. FERRY, OF MURRAY, IDAHO.

DESIGN FOR A WHEELED TOY.

59,343.

Specification for Design. Patented Oct. 11, 1921.

Application filed May 17, 1921. Serial No. 470,484. Term of patent 7 years.

To all whom it may concern:

Be it known that I, EUDORA B. FERRY, a citizen of the United States, residing at Murray, in the county of Shoshone and the State of Idaho, have invented a new, original, and ornamental Design for Wheeled Toys, of which the following is a specification, reference being had to the accompanying drawings, forming a part thereof.

The figure is a perspective view of a wheeled toy.

I claim:—

The ornamental design for a wheeled toy substantially as shown.

EUDORA B. FERRY.

Witnesses:

D. L. BUNDY,
Mrs. DELOS L. BUNDY.
